UNITED STATES PATENT OFFICE.

KARL GUSTAV MAXIMILIAN REICHEL, OF HANOVER, GERMANY, ASSIGNOR
TO WAGENBAUANSTALT UND WAGGONFABRIK FÜR ELEKTRISCHE
BAHNEN (VORM. W. C. F. BUSCH) ACTIENGESELLSCHAFT, OF BAUTZEN,
GERMANY.

AUXILIARY FLUID-PRESSURE APPARATUS FOR INSTANTLY STARTING STEAM-ENGINES.

SPECIFICATION forming part of Letters Patent No. 730,157, dated June 2, 1903.

Application filed February 10, 1903. Serial No. 142,740. (No model.)

To all whom it may concern:

Be it known that I, KARL GUSTAV MAXIMILIAN REICHEL, a subject of the King of Prussia, Emperor of Germany, residing at 8^a Clemensstrasse, Hanover, in the Province of Hanover and Empire of Germany, have invented new and useful Improvements Relating to Auxiliary Fluid-Pressure Apparatus for Instantly Starting Steam-Engines, of which the following is a specification.

My invention relates to apparatus designed for instantaneously working steam-vehicles and fire-engines, and has for its object to enable such vehicles and engines to be kept ready, on an alarm being given, for immediate work by the use of compressed air or gas, thus obviating the necessity of first getting up steam. The apparatus comprises a receptacle for compressed air or gas and a device serving to regulate the pressure of the air or gas and included in the pipe which connects the receptacle with the steam-generator. From the generator the compressed air or gas is supplied to the steam-engine until the pressure of the steam got up in the generator reaches its normal pressure, the admission of the compressed air or gas to the steam-generator being interrupted by an automatic checking or stopping device likewise provided in the said pipe.

In the drawings, Figure 1 is a general view of the apparatus, and Fig. 2 a section showing a detail.

The compressed air, carbonic-acid or like gas is contained in the receptacle *a* carried on the vehicle. For regulating the supply of

compressed air or gas which passes from this receptacle to the generator *b* through the pipe *c* use is made of a pressure-reducing device *d* of any known type. The pipe *c* is automatically cut off from the generator by a return-valve *e* included in this pipe, such valve being closed in opposition to the pressure of the air or gas by the steam in the generator on reaching the normal pressure. The return-valve *e*, a section of which is represented in Fig. 2 to a larger scale, does not differ in construction from that of an ordinary return-valve. It is connected with a stop-valve *f* of the common type, which serves for shutting off the pipe *g* leading from the generator to the steam-engine.

What I claim as my invention, and desire to secure by Letters Patent, is—

Apparatus of the character described, comprising a steam-generator, a receptacle for compressed gas, a pipe connecting the generator with the said receptacle, means for reducing the pressure of the gas coming from the receptacle and means for automatically shutting off the pipe from the generator on the steam in the latter reaching its normal pressure, substantially as and for the purpose set forth.

In testimony whereof I have signed my name to this specification in the presence of two subscribing witnesses.

KARL GUSTAV MAXIMILIAN REICHEL.
